CLAIM

The ornamental design for a straw component, as shown and described.

DESCRIPTION

FIG. 1 is a perspective view of a straw component showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the straw component where the straw component is in a configuration of use.

The broken lines in FIGS. 1-8 depict portions of the straw component that form no part of the claimed design. The other broken lines in FIG. 9 showing a bottle boy depict environment that form no part of the claimed design.
